UNITED STATES PATENT OFFICE

151,077

DESIGN FOR A BAKING IRON GRID

Minnie Severson, Mapleton, and Delilah Kraske,
Waseca, Minn.

Application May 23, 1947, Serial No. 139,224

Term of patent 14 years

(Cl. D81—26)

To all whom it may concern:

Be it known that we, Minnie Severson and Delilah Kraske, citizens of the United States, residing, respectively, at Mapleton, in the county of Blue Earth and State of Minnesota, and Waseca, in the county of Waseca and State of Minnesota, have invented a new, original, and ornamental Design for a Baking Iron Grid, of which the following is a specification, reference being had to the accompanying drawing, forming a part thereof.

Figure 1 is a face view of a baking iron grid, showing our new design.

Figure 2 is a partial sectional view taken along the line 2—2 of Figure 1.

We claim:

The ornamental design for a baking iron grid, as shown.

MINNIE SEVERSON.
DELILAH KRASKE.
